Application filed July 10, 1893. Serial No. 480,070. Term of patent 3½ years.

To all whom it may concern:

Be it known that I, DE VER H. WARNER, a citizen of the United States, residing at Bridgeport, in the county of Fairfield and State of Connecticut, have invented and produced a new and original Design for a Corset, of which the following is a specification.

My invention relates to a new and original design for corsets, and it consists in a corset having the ornamentation substantially as hereinafter described, and as illustrated in the accompanying drawing in which is shown one-half or section of a corset embodying my design.

In the drawing, A represents one-half or section of a corset, and α the usual covered stays extending from the upper to the lower edge of the corset section. Extending from the lower front edge of the corset is a strip or zone b which extends in a semi-circle over the hip portion to the rear lower edge of the corset A. A strip c extends from the front edge of the corset A diagonally across the stays α to the upper edge of the corset, presenting an ornamental and finished appearance thereto. 25

What I claim is—

The design for a corset, consisting of a “zone” strip extending in a semi-circle from the lower front edge of the corset to the rear lower edge thereof, and a strip extending from 30 the front edge of the corset section diagonally across the stays to the upper edge of the corset, substantially as described.

In testimony whereof I have signed my name to this specification in the presence of 35 two subscribing witnesses.

DE VER H. WARNER.
